OVERSPEED PREVENTING MECHANISM

David J. Conant, Cleveland Heights, Ohio, assignor to Jack & Heintz, Inc., Bedford, Ohio, a corporation of Ohio

Application February 18, 1943, Serial No. 476,342

3 Claims. (Cl. 200—80)

The present invention relates to a novel governor operated circuit breaker to prevent overspeeding of an electric motor or motor operated device.

In energizing inertia starters on aircraft engines it is customary where a source of power is available to employ a portable external electric energizer to accelerate the flywheel in the starter to a high speed. Such energizers are made sufficiently powerful for the largest engines and starters under adverse conditions, and are liable to overspeed, particularly when applied to smaller engines and starters. The object of the present invention is to provide a rugged and reliable circuit breaker responsive to motor speed to prevent overspeeding of an energizer motor.

In accordance with the patent statutes a preferred embodiment of the invention is illustrated in the accompanying drawing in which:

Figure 1 is a fragmentary sectional view through an energizer of the type referred to, showing the governor and circuit breaker of the present invention in their relation to the motor of the energizer; and

Figure 2 is an end view, looking from the left in Figure 1, with the switch housing broken away to show the operating parts therein.

The numeral 1 refers to an energizer housing containing a motor having an armature 2 carried at one end in a rear bearing 3. The bearing 3 is mounted in a bearing housing 4 which also accommodates a governor for operating a circuit breaker. The governor comprises a pair of weights 5 pivotally mounted at 6 on a U-shaped member 7 on the end of the armature shaft 8. Each weight 5 is provided with a bell crank arm 9 adapted to bear against a head 10 on an axially disposed pin 11. The pin 11 is rotatably carried in a plunger 12 which is mounted for axial and rotative movements in the end of bearing housing 4. The plunger 12 is biased inwardly of bearing housing 4 by means of a spring 13 abutting the flange 14, the inward movement being limited by snap ring 15.

The circuit breaker is designated generally by the numeral 20 and is mounted on a portion 21 of the energizer adjacent the bearing housing 4. The circuit breaker contains two terminal posts 22 and spring contact fingers 23 in circuit with a main line to the energizer motor, this circuit being normally maintained through an annular conductor band 24 on a plunger 25. The plunger 25 has an enlarged hollow portion 26 slidable in a guide 27, and a reduced extension 28 slidable in a guide 29. A compression spring 30 housed

within the hollow portion 26 serves to bias the plunger 25 to the right as viewed in Figure 2 with the shoulder 31 of enlarged portion 26 abutting a release lever 32 pivoted on a member 33. A torsion spring 34 serves to bias lever 32 against the plunger 25. The plunger and contacts are preferably contained within a two part housing comprising a base 35 having means of attachment to the portion 21 of the energizer, and a cover 36 having a post or boss 37 carrying the member 33 externally of said cover. One end of the lever 32 projects through an opening in cover 36 to engage the plunger 25 in the manner of a locking sear, and the other end has an angle portion 38 disposed for engagement by plunger 12 in the governor.

The various parts normally assume the positions shown in full lines, but are operative to open the motor circuit upon overspeeding of the motor.

20 The governor is designed so that at a predetermined critical speed the weights 5 are effective to move the bell crank arms 9 against the force of spring 13, to move plunger 12 outwardly. This motion is transmitted to the release lever 32 which is thereby brought to approximately the broken line position in Figure 1, causing the inner end of lever 32 to clear the shoulder 31 on plunger 25. Plunger 25 then snaps to the right in Figure 2, carrying conductor band 24 beyond the contact fingers 23 and opening the circuit to the motor. The open circuit position of plunger 25 is indicated by broken lines in Figure 2, the shoulder 31 having been stopped by guide 29.

25 The projecting end 28 of plunger 25 constitutes a reset button and is disposed to project outside the energizer housing 1 in the open circuit position. After a circuit breaking operation the governor plunger 12 will be again retracted as the motor slows down, and spring 34 will cause the inner end of release arm 32 to move into contact with plunger 25. Extension 28 may then be manually depressed until lever 32 snaps behind shoulder 31 to hold the conductor band 24 again under contact fingers 23 to reestablish the motor circuit. If the motor again overspeeds, the cycle of events to open the circuit will be repeated, and the circuit breaker may be again reset thereafter.

30 By virtue of the annular contact 24 the wear may be distributed therearound to greatly prolong the life of the circuit breaker, thereby reducing the weight and size of the parts to produce a prescribed number of operations before failure.

35 Various changes and modifications will occur to those skilled in the art, and it is to be under-

stood that the invention is to be limited only by the scope of the prior art and the appended claims.

I claim:

1. Overspeed preventing mechanism for a motor driven shaft comprising a bearing housing receiving an end of said shaft and its associated bearing therein, a pair of governor weights within said housing and rotatable with said shaft, a pin axially movable by said weights, a hollow plunger receiving said pin therein, said plunger being journalled in said bearing housing and projecting therethrough, a flange on said plunger within said housing, a compression spring surrounding said plunger and bearing against said bearing housing and said flange to retract said plunger, a locking sear lever engageable gradually by said plunger to release a spring biased switch plunger by movement at right angles thereto, and a bridging contact on said switch plunger adapted to normally bridge a pair of spring contact fingers to close a circuit for energizing said motor and adapted to move away from said contact fingers with a snap action to open said circuit when released by said lever.

2. Overspeed preventing mechanism for a rotating shaft comprising a governor plunger adapted to be extended from a rest position in response to overspeeding of said shaft, a circuit breaker for controlling a motivating power supply for rotating said shaft, said circuit breaker comprising a pair of spaced contacts, a switch plunger movable between said contacts, a bridg-

ing contact on said plunger, a locking sear lever for holding said plunger in bridging relation with said pair of contacts, and spring means urging said plunger to open circuit position, said lever being arranged for gradual actuation by said governor plunger to move at right angles to said switch plunger to release said switch plunger to move said bridging contact away from said spaced contacts with a snap acting movement at a predetermined speed of said shaft.

3. A circuit breaker adapted for actuation by a governor to prevent overspeeding of a power driven member comprising a housing, a pair of aligned guides in said housing, a cylindrical plunger slidable in said guides, a pair of contact fingers engageable with said plunger, an annular contact bridging element on said plunger, a hollow portion in said plunger, a spring in said hollow portion to bias said plunger to open circuit position, a shoulder on said plunger adapted to abut one of said guides to limit the movement of said plunger in circuit opening position, a portion of said plunger extending through said housing to serve as a manual resetting button, and a locking sear lever pivotally mounted on said housing for movement at right angles to said plunger, one end of said lever extending within said housing to engage said shoulder to hold said plunger normally in closed circuit position and one end of said lever extending outwardly from said housing for gradual actuation by said governor to release said plunger for a snap acting circuit opening movement.
